UNITED STATES PATENT OFFICE.

VALDA W. POTTER, OF OELWEIN, IOWA.

VALVE-ACTUATING MECHANISM FOR GAS-ENGINES.

951,965.

Specification of Letters Patent. Patented Mar. 15, 1910.

Application filed October 27, 1909. Serial No. 524,931.

To all whom it may concern:

Be it known that I, VALDA W. POTTER, a citizen of the United States, residing at Oelwein, in the county of Fayette and State 5 of Iowa, have invented certain new and useful Improvements in Valve-Actuating Mechanism for Gas-Engines; and I do hereby declare the following to be a full, clear, and exact description of the invention, such as 10 will enable others skilled in the art to which it appertains to make and use the same.

My invention relates, generally, to gas-engines and, more particularly, to a novel form of valve-actuating mechanism therefor.

The object of the invention is, primarily, to provide a novel form of valve-actuating mechanism, which, while being extremely simple in construction, shall be reliable and 20 positive in its action.

Other subsidiary objects of improvement will appear as the specification proceeds and the nature of the invention more fully appears.

25 In the accompanying drawings, forming part of my application for patent, and in which like letters of reference indicate corresponding parts, I have, for illustrative purposes, shown my improvements as embodied in a gas-engine; but it will be understood, of course, that I do not confine my invention to such use, as my improvements are 30 equally applicable for use in connection with forms of engines, other than gas-engines.

35 In the drawings: Figure 1 is a side elevation of a gas-engine embodying my improvements; Fig. 2 is a bottom plan view, certain parts being shown in section; Fig. 3 is an end view; Fig. 4 is a detached detail view 40 of one of the levers; and Fig. 5 is a detached detail view of the duplicate cam-wheels.

Referring, now, in detail to the drawings: A designates the frame or supporting-base of the gas-engine; and b, b designate the 45 valve-stems, movement of which is controlled by my valve-operating mechanism, now to be described.

Carried by the main shaft C of the engine is a broad-faced pinion c, in mesh with, and 50 driving in unison, duplicate cam-wheels d, d, revolvably mounted on a shaft D projecting from the frame A. Each cam-wheel d is provided with circumferential gear-teeth d²; and one face of each wheel is recessed, 55 as at d³, and provided with a cam d⁴. The relative position of these cam-wheels on the

shaft D is back to back, as shown in Figs. 3 and 5. The cam-wheels d are exact duplicates of each other in every respect. Pivotally supported at their lower ends on a 60 shaft E projecting from the frame A are duplicate levers e, e, each preferably provided with a hub-portion e' at its lower end, and carrying at its upper end a roller e² working against the circular rim or edge- 65 wall d⁶ of the recessed portion d³ of the cam-wheel d; the rollers, at the proper time in the rotation of the cam-wheels, being engaged by the cams d⁴, d⁴ to rock the levers e, e. Links f, f are each pivotally secured, 70 at one end, to the corresponding lever e and, at the other end, to the shortest arm g' of a lever g, having an offset g², in the nature of a collar loosely embracing a shaft h carried by a casting or standard H secured to 75 the under side of the piston-chamber I. Each lever g carries, also, an arm g³, which is, at one end, formed as a collar g⁴ loosely embracing the shaft h and, at the other end, g⁵, loosely engages the valve-stem b. Each 80 valve-stem b is provided with a spring b', which serves to hold the valves in their seats, and the cam-rollers e² against the rim d⁶ and against the cams d⁴, as is obvious.

It is believed that the operation of the 85 valve-actuating mechanism will be apparent; but, briefly stated, it is as follows: Rotation of pinion c revolves the cam-wheels d, d in unison, the rollers e², e² traveling around the rims d⁶ of the recessed portions 90 d³, d³ until they are engaged by the cams d⁴, d⁴, when the levers e are swung backward on their pivots E, thus drawing rearward the links f, f and rocking the levers g, g on their pivot h and consequently rocking the arms 95 g³, g³ of said levers to actuate the valves.

It is often necessary, in stationary gas-engines, especially those for farmers' use, for the engineer to reverse his engine; hence the purpose of the duplicate cam-wheels d, 100 d is to enable the operator to change the direction of his engine. This is accomplished by loosening the set-screw e' securing the levers e, e to the shaft E, slipping the front lever e outward, and then slipping the front 105 or back cam-wheel d out of mesh with the pinion c and turning said cam-wheel to set it back or forward say four cogs or more teeth, and, in this position, slipping said wheel into mesh again with the pinion c and 110 tightening up the set-screw e'. This, as is obvious, changes the former relative posi-

tions of the cams d^4 , d^4 , causing the explosion to take place either on the down-, or the up-stroke of the crank.

The construction of the device is susceptible of modification in detail, without sacrificing the advantages or affecting the spirit of the invention; and all such modifications and changes as come within the scope of the appended claim, constitute no departure 10 from the invention, herein described, illustrated, and claimed.

Having thus fully described my invention, what I claim as new and desire to secure by Letters-Patent is:

15 In a gas-engine having two valves, a valve-actuating mechanism therefor, comprising a broad-faced pinion, independent, duplicate

gear-wheels meshing with, and driven in unison by, said pinion, and positioned back to back and each having a cam, mechanism 20 intermediate said gear-wheels and said valves and intermittently engaged and moved by said cams, to actuate said valves, and means permitting disengagement of one of said gear-wheels from mesh with said pinion, for 25 changing the relative position of said cams.

In testimony whereof, I affix my signature, in the presence of two subscribing witnesses.

VALDA W. POTTER.
